UNITED STATES PATENT OFFICE

IRBY TINDAL, OF GREENVILLE, ALABAMA

STARTER SWITCH

Application filed May 14, 1928. Serial No. 109,186.

This invention appertains to circuit closures and more particularly to a novel starter switch for automobiles.

The primary object of the invention is to provide a starter switch embodying an electromagnet, which upon being energized, serves as means for bringing the contact points of the starter circuit into engagement, the circuit for the magnet having a control button located at a convenient point to the steering wheel of the vehicle, whereby the necessity of providing the usual foot switch and the difficulties contingent therewith is eliminated.

Another object of the invention is to provide a starter switch embodying a pair of substantially parallel resilient contact arms, one of which has connected therewith an electromagnet for attracting the other arm which constitutes the armature therefor.

A further object of the invention is to provide a starter switch of simple and durable character which can be placed upon the market and incorporated with a conventional starter circuit at small cost.

With these and other objects in view the invention consists in the novel construction, arrangement and formation of parts, as will be hereinafter more specifically described, claimed and illustrated in the accompanying drawings, in which,

Figure 1 is a diagrammatic view showing the improved starter switch incorporated in the starter circuit,

Figure 2 is an end elevation of the switch,

Figure 3 is a side elevation of the switch showing the base thereof in longitudinal section and illustrating the method of connecting the arms with the base, and

Figure 4 is a perspective view showing the novel resilient arms of the switch.

Referring to the drawings in detail where-in similar reference characters designate corresponding parts throughout the several views, the letter A generally indicates an improved starter switch which comprises a flat base plate 5 preferably formed of electric conducting material. The base plate 5 can be connected with a stationary portion of the vehicle at any desired point.

Arranged upon the outer face of the base plate are closing arms 6 and 7 which are formed from resilient material. These arms are normally arranged in a substantially parallel plane and the arm 7 is provided with a right angularly extending attaching foot 8 at its inner end. A connecting bolt 8 is employed for holding the arm 7 in position and extends through the foot 8 and the base plate 5 and in order to insulate the arm from the base plate a suitable washer or collar of non-electric conducting material 10 is provided. As shown, the bolt extends through said collar or washer and nuts 11 are threaded upon the bolt and hold the same in adjusted position. The inner end of the arm 6 is likewise provided with a right angularly extending attaching foot 12 and a bolt 13 is employed for connecting the foot to the base plate and the arm is arranged directly in front of and in longitudinal alinement with the arm 7. The upper end of the arm 6 is provided with an inwardly directed extension 14 and the inner face of the extension and the inner face of the arm 7 adjacent to the free ends thereof are provided with relatively large contact buttons 15 and 16.

An electromagnet 17 is secured to the inner face of the arm 7 directly inward of the extension 14 and it is to be noted that the arm 6 with its extension conforms to the configuration of the magnet. The arm 6 constitutes an armature for the electromagnet 17, whereby upon the energizing of the magnet the arm 6 will be flexed for bringing the buttons 15 and 16 into contact.

The base plate 5 forwardly of the arms 6 and 7 is provided with a pair of spaced binding posts 18 and 19 to which are connected the terminals of the electromagnet 17 by means of wires 20 and 21. The binding posts 18 and 19 are insulated from the base plate 5 by suitable insulating washers or collars 22. Thus the arm 7 and the two binding posts 18 and 19 are insulated from the base plate while the arm 6 is grounded thereto.

In Figure 1 of the drawings I have shown one method of incorporating the switch in the starter circuit, and as shown, the lead wire 23 from the conventional battery 24 is con-

nected with the binding post 18. The return wire 25 of the battery is grounded to the frame of the vehicle in the usual way. A wire 26 is connected to the other binding post 19 of the magnet and has incorporated in the 5 length thereof a suitable switch 27 which can be of a push button type. This wire 26 is also grounded to the frame of the vehicle as at 28. Upon the closing of the switch 27 it is 10 obvious that the magnet 17 will be energized causing the flexing of the arms 6 and 7 and the contacting of the buttons 15 and 16. A branch wire 23' is connected with the wire 23 and to the upper end of the arm 7. A wire 29 15 is grounded to the base plate 5 and leads to one terminal of the starting motor 30, the other terminal of which is grounded to the frame of the vehicle as at 31 by a wire 32. By this arrangement when the buttons 15 and 16 are in 20 contact the circuit will be closed through the motor.

From the foregoing description it can be seen that I have provided an exceptionally simple type of magnetic starter switch for automobiles in which the circuit can be conveniently closed by the operator of the vehicle.

Changes in details may be made without departing from the spirit of the invention or the scope of the subjoined claim.

What I claim is:

30 A starter switch comprising a base plate, a pair of arms insulated from each other and carried at their inner ends by said base plate, at least one of said arms being resilient, one 35 arm being straight, an electromagnet carried by said last named arm, the other arm acting as an armature to be attracted by said electromagnet upon energization thereof, said armature arm extending from the base parallel to the other arm to a point slightly beyond the magnet and being bent at a right angle providing an off-set, then extending again parallel to the first arm whereby the free ends of said arms are arranged adjacent and parallel to each other, and electrical contacts carried by the adjacent faces of the free ends of 40 said arms.

45 In testimony whereof I affix my signature.
IRBY TINDAL.
